The ornamental design for a set of solar pool lights, as shown and described.

DESCRIPTION

FIG. 1 is a perspective view of a first part of the set of solar pool lights showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a perspective view of a second part of the set of solar pool lights showing my new design;

FIG. 10 is a perspective view thereof from another angle;

FIG. 11 is a left side elevational view thereof;

FIG. 12 is a right side elevational view thereof;

FIG. 13 is a rear elevational view thereof;

FIG. 14 is a front elevational view thereof;

FIG. 15 is a top plan view thereof; and,

FIG. 16 is a bottom plan view thereof.
